[57] **ABSTRACT**

A hand and foot operated swing including frame means connected to form a parallelogram and supporting a seat thereon, a front support member comprising part of the frame means and having hand grips and foot pedals of different heights thereon for enabling a rider to impart force to the hand grips and foot pedals to cause swinging movement to said swing.

HAND AND FOOT OPERATED SWING**BACKGROUND OF THE INVENTION**

The present invention provides a simple and effective swing which is propelled by the pumping action of a person riding said swing and which affords at the same time an entertaining toy and a therapeutic device.

Prior art swings of this nature often are quite bulky and difficult for some persons to propel. For example, in these devices a child or other person riding the swing must overcome the inertia of the combined weight of the swing and of the weight of the rider in order to propel the swing or to cause initial movement thereof. Such a device is shown, for example, in U.S. Pat. No. 2,900,010 issued to R. J. Oliver. In this swing the top and bottom frame members 10 and 10' are horizontally disposed and are pivotally connected at the upper and lower ends, respectively, of the back frame member 12 and near the upper and lower ends, respectively, of the front frame member 11. The rider is seated on the top frame member intermediate the ends thereof and in order to overcome the inertia of the combined weight of the swing and the rider, substantial force must be exerted on the foot pedals and hand grip portions of the swing due to the particular manner in which the frame members are interconnected.

In one embodiment of the present invention on the other hand, the top and bottom frame members are disposed at an angle to the horizontal with the seat portion resting on the top frame member intermediate the ends thereof and accordingly supported at an angle to the horizontal. The top and bottom frame members are both pivotally connected at one end near the lower end of back support strap 2 and are both connected at their other end near the middle of front support strap 1. With this construction, a more beneficial mechanical advantage is afforded and the flexible chains or other suitable suspension means are disposed at a position such as not to interfere with the rider.

SUMMARY OF THE INVENTION

The present invention relates to a self-propelled swing which is both an entertaining toy and a therapeutic device.

The swing includes a frame having top and bottom frame members inclined to the horizontal and pivotally fixed at opposite ends to upstanding supporting frame members to form a parallelogram and arranged such that a rider on the swing can easily manipulate the swing by exerting force on the hand grip and foot pedal portions and yet is free of interference with the support means for the swing.

BRIEF DESCRIPTION OF THE DRAWINGS

FIG. 1 is a top perspective view of the swing with the seat removed for clarity.

FIG. 2 is a top plan view of the swing.

FIG. 3 is a side view in elevation of the swing.

DETAILED DESCRIPTION OF THE INVENTION

Referring now to the drawings wherein like reference numerals refer to like parts throughout the several views, a preferred embodiment of the swing comprises a frame F including a front support strap 1 and a back support strap 2 of greater length than the front strap

and normally suspended at a greater elevation than the front strap.

5 A pair of bottom frame straps 3 and 4 are pivotally connected at one end thereof on opposite sides and at the lower end of the back support strap 2 by means of a bolt or the like 5. The other ends of the bottom frame straps 3 and 4 are pivotally connected on opposite sides and intermediate the upper and lower ends of the front support strap 1 by means of a bolt or the like 6.

10 15 A pair of angle irons 7 and 8 arranged in back-to-back relationship are pivotally connected at one end thereof on opposite sides of and spaced upwardly from the lower end of back support strap 2 by means of a bolt or the like 9 and are pivotally connected at their opposite ends on opposite sides of and medially of the ends of front supporting strap 1 by means of a bolt or the like 10, said bolts being passed through the vertically extending flanges of the angle irons with the other 20 flange of each iron directed laterally outwardly from opposite sides of the swing.

25 A seat S formed of hard wood or the like is fixed medially of the ends and on the top surfaces of the laterally extending flanges 11 and 12 of the angle irons 7 and 8 by suitable means such as bolts 13 or the like passed downwardly through the seat and between the confronting vertical flanges of the angle irons.

30 The swing is suspended for swinging movement by means of flexible chains 14 or the like connected to the ends of elongated rods 15 and 16 or the like received through holes adjacent the upper ends of the front and back supporting straps 1 and 2, respectively, and welded therein to prevent undesired relative movement between the elongate rods 15 and 16 and supporting straps 1 and 2. A suitable loop 17 or other attaching means is welded or otherwise fixed at each end of the elongate rods to which the flexible chains or the like are connected for supporting the swing for swinging movement. The elongate rod 15 fixed to the front supporting strap 1 serves as a hand grip for the rider to grasp to prevent the rider from falling off the swing and to enable the rider to impart propulsive force to the swing to propel the same.

35 40 45 A lower elongate rod 18 comprising a foot pedal is received through a hole adjacent the lower end of the front supporting strap 1 for receiving the feet of an adult rider or the like and is welded or otherwise suitably fixed in position. A second elongate rod 19 comprising a foot pedal for children or the like is received through a hole spaced upwardly from the lower end of front supporting strap for receiving the feet of small children or the like and is similarly welded in position.

50 55 60 65 By exerting force on the hand grip and foot pedal portions of the swing, the rider may impart motion thereto. As seen most clearly in FIG. 3, the top and bottom frame members are inclined to the horizontal and are spaced relatively close together with respect to the length of the front and back support straps thus affording a particular mechanical advantage. Of course, the seat and top and bottom frame members could be horizontally disposed if desired.

65 By way of specific example, the front supporting strap 1 is formed of iron and is approximately 30 inches long, 1 1/2 inches wide and 1/4 inch thick; the back supporting strap is formed of iron and is approximately 36

inches long, 1 $\frac{1}{2}$ inches wide, and $\frac{1}{4}$ inch thick; the bottom frame straps are formed of iron and are approximately 26 $\frac{1}{2}$ inches long, 1 inch wide and $\frac{1}{4}$ inch thick and are pivotally connected at one end thereof to the back supporting strap approximately 1 inch up from the lower end thereof and are pivotally connected at the other end thereof to the front supporting strap 1 approximately 11 inches upwardly from the bottom end thereof, the pivotal connections being made by $\frac{1}{2}$ inch diameter bolts received through 9/16 inch diameter holes. As illustrated in FIG. 3, the bottom end of back supporting strap 2 is about 3 inches higher in elevation than the bottom end of the front supporting strap 1.

The top frame angle irons 7 and 8 are spaced upwardly approximately 4 inches from the bottom frame straps and are approximately 26 $\frac{1}{2}$ inches long, 1 $\frac{1}{2}$ inches wide and $\frac{1}{4}$ inch thick.

The bottom foot pedal 18 is fixed to the front supporting strap approximately 1 inch up from the bottom end thereof and comprises a rod 12 inches long and 5/8 inch in diameter. The top foot pedal 19 is fixed to the front supporting strap approximately 6 inches up from the bottom end thereof and comprises a rod 8 inches long and $\frac{1}{2}$ inch in diameter.

The elongate supporting rods 15 and 16 at the upper ends of the supporting straps 1 and 2 are approximately 20 inches long and 5/8 inch in diameter, and the seat S is formed of hard wood or other suitable materials and is approximately 1 inch thick.

While a specific embodiment of the invention has been described herein, it is not intended that the invention be limited to such details of construction but that other and different constructions such as fall within the scope of the appended claims are intended to be covered as well.

I claim:

1. A self propelled swing comprising a vertical, flat, elongate, straight, rigid front support strap, a similar vertical, elongate, flat, straight, rigid, back support strap spaced rearwardly of and at a higher elevation than the front support strap and parallel thereto,

an elongate, straight, swing support rod extending through each of the front and back support straps closely adjacent the upper ends thereof and each fixed medially thereof to the support straps and extending horizontally considerably beyond opposite sides of each strap, the swing support rod on the front support strap defining a hand grip for the user of the swing,

an elongate flexible support means secured at each end of each swing support rod,

a pair of similar, rigid, straight, elongate, side-by-side aligned, angle irons comprising a seat frame, each angle iron including an integral, flat, horizontal web and a vertical web and each with similar opposite end portions thereof pivotally connected to the front and back support straps, respectively, upwardly from the bottom end portions of each of the straps,

said pivotal connections in the front strap being considerably above the pivotal connections in the back strap, the angle irons thus being permanently considerably inclined upwardly from the back strap to the front strap,

a seat fixed on the flat webs of the inclined angle irons substantially medially of the length thereof,

a pair of similar, flat, rigid, bottom frame straps spaced closely below the angle irons in inclined, parallel relationship thereto,

the end portion of each rigid, flat, bottom frame strap in contact with opposite, adjacent side portions of each front and back support strap, pivot means connecting the opposite end portions of the bottom frame straps to the front and back support straps, respectively, and

two vertically spaced apart, elongate, foot engaging means in a lower portion of the front support strap below the bottom frame straps, the foot engaging means projecting laterally beyond opposite sides of the bottom portions of the front support strap, thus providing foot engagement by the user with either of the spaced apart, projecting foot engaging means.
